D. B. BAKER,
CLOTHES DRYING RACK,
APPLICATION FILED APR. 12, 1921.

1,425,231.

Patented Aug. 8, 1922.

FIG. 1.

UNITED STATES PATENT OFFICE.

DAVID B. BAKER, OF HOQUIAM, WASHINGTON.

CLOTHES-DRYING RACK.

1,425,231.

Specification of Letters Patent. Patented Aug. 8, 1922.

Application filed April 12, 1921. Serial No. 460,858.

To all whom it may concern:

Be it known that I, DAVID B. BAKER, a citizen of the United States, residing at Hoquiam, in the county of Grays Harbor and State of Washington, have invented a new and useful Clothes-Drying Rack, of which the following is a specification.

This invention relates to clothes drying racks.

10 The object is to provide a rack for the drying of clothes or other articles which is adapted for use in conjunction with an ordinary hot water boiler as found in the usual kitchen, so as to utilize the heat of 15 the boiler as a drying medium for the clothes.

Another object is to provide a device of this class which may be manufactured and sold at a low cost by reason of the fact that 20 the same may be made of ordinary strap iron, suitably stamped and bent to form to accomplish the purposes sought, and which will support a plurality of towels, or other articles, in a manner to permit of free circulation of air while being subjected to the 25 drying effects of the heated boiler.

A full and complete understanding of the invention may be obtained from a consideration of the following detailed description, 30 taken in connection with the accompanying drawing forming a part of this specification; it being understood that while the drawing shows a practical form of the invention, the latter is not to be confined to 35 strict conformity therewith, but may be changed or modified, so long as such changes or modifications mark no material departure from the salient features of the invention, as specifically pointed out in the appended claims.

In the drawing, in which similar reference characters designate corresponding parts throughout the several figures:—

Figure 1 is a front elevation of the upper 45 portion of an ordinary water boiler showing the improved drying attachment applied thereto;

Figure 2 is a vertical sectional view of the same, taken at right angles to Figure 1;

50 Figure 3 is a top plan view of the subject matter of Figure 1;

Figure 4 is a detail sectional view taken on the line 4—4 of Figure 2.

The invention is illustrated in the drawing as applied to an ordinary kitchen boiler 55 1, having the usual concavo-convex upper

end 2, which supports, in spaced relation, the customary inlet pipe for cold water and the outlet pipe 4 for hot water, though it is to be understood that the invention may be 60 advantageously used in connection with any other upright element having heat radiating properties.

The invention comprises upper and lower spaced substantially semi-circular bands or 65 arms 5 and 6 respectively, which are formed of suitable strap iron of dimensions to give sufficient strength to support a quantity of clothes or other articles and struck on a radius to agree with the radius of the boiler 70 1, and slightly greater than the same, so as to freely rotate therearound.

The arms or bands extend substantially half-way around the boiler and are connected together at their central points by a 75 vertical hanger or support 7, formed of the same material, and suitably riveted or otherwise secured thereto, as indicated at 8, and the said bands 5 and 6 are provided with a series of out-standing, upwardly-curved 80 hooks 9 secured to the bands as by upsetting prolongations of the hooks where passing through suitable apertures of the bands as indicated at 10 in Figure 2.

The hooks 9 are attached to their respective bands, each series in alternate or staggering arrangement to those of the other band, so that the articles hanging upon the upper set of hooks will not interfere with those suspended from the lower set, as will 90 be understood, and that all of said articles may lie adjacent to the surface of the boiler.

The upper end of the hanger 7 is bent inwardly, as at 11, to lie above the top of the boiler and is provided, adjacent to its upper 95 end, with a pair of longitudinally-disposed, spaced slots 12 for the reception of a pair of bolts 13, which traverse suitable apertures of the lower extremity of an extension arm 14, the nuts of the bolts 13 preferably lying beneath the arm 14 and serving to bind the extension rigidly in adjusted relation to the upper end of the hanger 7.

The upper end of the extension arm 14 is bent, as at 15 to lie horizontally and extends to a point over the center of the boiler, and is suitably apertured for the reception of a pivotal bolt 16 which mounts the rack for swinging movement about the axis of the boiler upon a deck-plate 17 having a 110 forwardly-extending tongue 18.

The plate 17 is thus located at what may

be termed the rear of the center of the boiler, and is adapted to rest upon the inlet and outlet pipes 3 and 4, with its forward edge, where merging into the tongue 18, 5 abutting against the ends of the usual elbows 3^a and 4^a as are in common use, and the said plate is provided with a pair of spaced, transversely disposed slots 19 arranged at right-angles to the pipes 3 and 4, 10 and has its outer, opposed edges turned slightly downward, as indicated at 20 in Figure 4 of the drawing.

A plate 21, similar to but smaller than the plate 17 and without the extension 18, 15 is located beneath the same and is adapted to bear against the under sides of the pipes 3 and 4, the said latter pipe 21 having slots 22 corresponding to the slots 19 aforesaid, and in registering relation therewith; and 20 having its outer edges curved upwardly, as 23, in opposed relation to the curved edges of the upper plate.

The plate 21 constitutes a clamping plate, and is held to the upper plate 17 by clamping bolts 24 which, by reason of the registering slots 19 and 22 providing for the lateral adjustment of said bolts, are brought to bear against the inner opposed sides of the pipes 3 and 4 whereby, when the nuts 25 30 are tightened, the deck-plate 17 is effectually held from lateral movement, and the elbows 3^a and 4^a preventing any forward or longitudinal movement of the said plate when the rack is supporting a load of clothes 35 or other articles.

The relative lateral movement of the bolts 24 permit of proper adjustment to fit the plates to pipes different distances apart so that the same may be applied to different 40 makes of boilers, and the slots 12 permit of the lower hanger arm 7 together with its attached hook-carrying bands 5 and 6 being arranged a greater or lesser distance from the vertical axis of the boiler so as to be 45 adaptable to boilers of varying diameters.

From the foregoing it will be seen that an extremely simple, and cheaply manufactured clothes drying rack has been provided which may be quickly adjusted to fit water 50 boilers of varying sizes, and securely attached to the same in position to allow of the application of towels, clothes or other articles so that the latter may lie adjacent to the heat-radiating surface of the boiler, 55 and that the same may be swung around the axis thereof, within limitations, to present any one of the several hooks of the upper or the lower series to the operator, for the purpose of hanging the articles thereon or 60 removing the same therefrom.

What is claimed is:

1. In combination with a hot water boiler, a clothes drying rack comprising a band in the shape of an arc of a circle and mounted 65 to move about the boiler, clothes supporting

means carried by the band, and means connected with the rack to suspend the same from the top of the boiler and in the longitudinal axis of the latter.

2. In combination with a hot water boiler, 70 a clothes drying rack comprising a series of curved bands, each having projecting clothes supporting hooks, and a hanger arm connected to the bands and holding them in spaced-apart relation, and means for pivoting the hanger arm to the top of the boiler so that the rack may be swung in a horizontal plane about the boiler.

3. In combination with a hot water boiler having inlet and outlet pipes located at the 80 top in close spaced relation, a supporting plate connected to said pipes, a clothes drying rack having a plurality of clothes supporting hooks, and means for pivotally connecting the rack to the plate in the vertical 85 longitudinal axis of the boiler, whereby the rack may be swung in a horizontal plane about the boiler.

4. In combination with a hot water boiler having inlet and outlet pipes extending 90 from the top thereof and arranged in close spaced relation, a clothes drying rack adapted to partially surround the boiler and having clothes supporting hooks extending therefrom, and means for pivotally connecting the clothes drying rack to said inlet and outlet pipes in the vertical longitudinal axis 95 of the boiler.

5. In combination with a hot water boiler having inlet and outlet pipes extending from 100 the top thereof in closely spaced relation to each other, plates clamped to said pipes, a clothes drying rack mounted to move in a horizontal plane below the top of the boiler, and means for pivotally connecting said 105 rack to one of said plates in the vertical longitudinal axis of the boiler.

6. In combination with a hot water boiler having inlet and outlet pipes extending from the top thereof in spaced relation to each other, supporting means clamped to said pipes, a clothes drying rack mounted to move in a horizontal plane about the boiler below the upper end thereof, and adjustable means connecting the clothes drying rack 115 to said supporting means.

7. In combination with a hot water boiler having inlet and outlet pipes extending from the top thereof in spaced relation to each other, a clothes drying rack comprising curved bands held in spaced relation from the boiler and movable about the same, each band carrying a plurality of clothes supporting hooks, a hanger arm connected to the bands and extending above the top of 125 the boiler, and means for pivotally connecting said hanger arm to said inlet and outlet pipes in the vertical longitudinal axis of the boiler.

8. In combination with a hot water boiler 130

- having inlet and outlet pipes extending from the top thereof in spaced relation to each other, supporting means clamped to said pipes, a clothes drying rack having 5 a series of curved bands held in spaced relation from the boiler, each band having a plurality of clothes supporting hooks, a vertical hanger connected to said bands and extending over the top of the boiler, an extension arm adjustably connected to said hanger arm, and means for pivotally connecting the extension arm to said supporting means in the vertical longitudinal axis of the boiler.
- 10 9. A clothes drying rack for attachment to a kitchen water boiler, comprising spaced upper and lower, semi-circular bands adapted to partially surround the boiler, a series of outwardly-extending, radially-disposed 15 hooks carried by each band, a vertically disposed hanger arm connecting the bands at intermediate points and having its upper end portion bent inwardly to extend over the top of the boiler and provided with 20 longitudinal slots, an extension arm fitting against the under side of said upper end portion and having slots in registering relation to the first-named slots for the reception of clamping bolts, the upper end of the extension arm being bent to lie in a 25 horizontal plane and provided with an aperture near its terminal, an upper plate adapted to rest upon the inlet and outlet pipes of the water boiler and having transverse slots, and a forwardly-extending tongue 30 having an aperture and projecting beneath the horizontal portion of the hanger-arm extension, a bolt traversing the apertures and pivoting the hanger to the supporting plate, a clamping plate adapted to bear 35 against the bottom sides of the inlet and outlet pipes in co-action with the first-named plate, and having transverse slots in registering relation to the first-named transverse slots, and clamping bolts adapted to 40 the same and movable inwardly or outwardly to fit against the opposed sides of the said pipes to rigidly clamp the plates, together with the attached hanging means, in 45 position upon the boiler. 50
- In testimony that I claim the foregoing as my own, I have hereto affixed my signature.

DAVID B. BAKER.
